UNITED STATES PATENT OFFICE.

ABNER D. BAKER, OF SWANTON, OHIO.

ROTARY ENGINE.

SPECIFICATION forming part of Letters Patent No. 440,125, dated November 11, 1890.

Application filed April 17, 1890. Serial No. 348,365. (No model.)

To all whom it may concern:

Be it known that I, ABNER D. BAKER, a citizen of the United States, residing at Swanton, in the county of Fulton and State of Ohio, have invented a new and useful Rotary Engine, of which the following is a specification.

This invention relates to rotary engines; and it has for its object to construct a concentric rotary engine which may utilize fluid-pressure of any description in such a manner as will gain the maximum amount of power in proportion to the energy expended.

A further object of my invention is to construct a motor of this class which shall be simple, durable, and efficient in operation.

With these ends in view the invention consists in the improved construction, arrangement, and combination of parts, which will be hereinafter fully described, and particularly pointed out in the claims.

In the drawings, Figure 1 is a side elevation of my improved engine, with one side of the casing removed so as to expose the interior construction. Fig. 2 is a vertical sectional view taken longitudinally through the shaft of the engine on the line 2 2 in Fig. 1. Fig. 3 is a side elevation showing the inner face of one of the cylinder-heads. Fig. 4 is a side elevation of the engine with one of the shaft-bearings detached. Fig. 5 is a detail end view of the rotary piston-head. Fig. 6 is a detail longitudinal sectional view showing the construction of said rotary piston-head or abutment. Fig. 7 is a detail view showing the rotary piston with the sliding piston in contact with the packing-strip of the casing between the inlet and exhaust ports. Fig. 8 is a detail view showing the guide-arms of the rotary piston-head and the piston or valve between the said guide-arms.

Like numerals of reference indicate like parts in all the figures.

The casing of my improved rotary engine is composed of the shell 1, having cylindrical bore 2, the heads or ends 3 3 of which are secured to the said shell or casing by means of stud-bolts 4 or in any suitable manner. The heads or ends 3 3 are provided with cylindrical laterally-extending sleeves 5 5,

which are eccentric to the bore of the cylinder. Suitably bolted to the outer ends of said sleeve are the bearing-blocks 6, having flanges 7 to receive the securing-bolts. The bearing-blocks 6 have bearings for the shaft 8, which is arranged concentrically with relation to the cylindrical bore of the shell.

9 designates the revolving piston-head, which consists of a cylindrical shell or body 10, having laterally-extending sleeves or tubular arms 11, which are journaled between the sleeves 5 and the bearing-blocks 6. Eccentric bearing rings or bushings 12 are interposed between the tubular arms 11 and the sleeves 5, and are secured in position by means of set-screws 13, extending through the flanges 7 of the bearing-blocks 6. These eccentric bearing-rings might with equal effect be arranged between the tubular arms 11 and the bearing-blocks 6, or two sets of said eccentric bearing-sleeves might be used on opposite sides of the tubular arms 11. The function of said eccentric bearing-sleeves is to admit of the adjustment of the revolving piston-head to compensate for wear upon the latter, such adjustment being effected by partially turning the bearing rings or sleeves, thereby raising the revolving piston-head when necessary to effect the desired adjustment.

The revolving piston-head is provided with guide-arms 14, extending diametrically through the said piston-head, and provided with a roller-joint 15, fitting a cylindrical recess 16 in one side of the revolving piston-head. The arms 14 are connected by means of a screw 18, which may be tightened whenever it shall be necessary to compensate for wear upon the piston-plate 19. The latter, which is fitted between the guide-arms 14, is keyed or mounted securely upon the shaft 8, and it is provided on the opposite side of said shaft with a weight or counter-balance 20. The outer end of the piston-plate 19 is at all times in contact with the interior surface of the casing of the machine, and its outer edge is provided with a groove 21, in which is seated a packing-strip 22, which is forced outwardly into contact with the bore of the cas-

ing by the action of suitably-arranged coiled springs 23. The end of the piston-plate is likewise grooved, as at 24, and provided with packing-strips 25, which are forced outwardly 5 into contact with the sides of the casing by means of coiled springs 26. A packing-strip 27, to bear against the side of the piston-plate, is also seated in a suitable groove in the inner side of one of the guide-arms 14, as will 10 be seen in Fig. 1 of the drawings.

The revolving piston-head is, as above described, arranged eccentrically in the casing, and is at all times in contact with the shell of the casing at one point. At this contact-point 15 the shell is provided with a groove 28, in which is seated a packing-strip 29, which is held in contact with the rotary piston-head by means of coiled springs 30, thereby making a steam-tight joint at the point of contact.

20 The heads or ends 33 of the casing are provided on their inner sides with annular grooves 31, which are concentric with the revolving piston-head. Said grooves are slightly inside the periphery of the said revolving piston-head, and in the said grooves are placed packing-rings 32, which by the action of springs 33 are held in contact with the said revolving piston-head, so as to effect steam-tight joints. The packing-rings 32 are 25 so arranged as to lap slightly over the packing-strips 25 in the ends of the piston-plate 19. At the point where the revolving piston-head is in contact with the cylindrical shell of the casing the packing-rings 32 are discontinued, and the ends of the casing are 30 provided with radial grooves 34, in which packing-strips 35 are placed, said packing-strips being actuated by coiled springs 36 to hold them in contact with the ends of the revolving 35 piston-head.

40 37 designates the steam-chest, which consists of a cylindrical chamber formed in one side of the shell or casing and having the steam-inlet 38. One end of the steam-chest 45 has a bearing for a rock-shaft 39, over the outer end of which is arranged a packing-gland 40 to form a steam-tight joint. The inner end of the rock-shaft 39 carries the oscillating valve 41, and the outer end of said 50 rock-shaft has a crank or wrist pin 42, which is connected by a pitman 43 with a similar crank 44 upon one end of the main shaft 8 of the engine. The cranks 42 and 44 are mounted adjustably upon their respective shafts by 55 means of set-screws 45. It will thus be seen that the crank 42 may be readily adjusted to so adjust the oscillating valve 41 as to cause the cut-off to be readily controlled and to cause said cut-off to take place at any desired 60 point which the piston may occupy in the cylinder. A steam-port 47 connects the steam-chamber 37 with the casing on one side of the contact-point between said casing and the revolving piston-head. An exhaust-port 48 is 65 formed in the casing on the opposite side of

said contact-point. Said exhaust-port is at all times open for the purpose of preventing back-pressure.

From the foregoing description, taken in connection with the drawings hereto annexed, 70 the advantages of my invention will be readily understood by those skilled in the art to which it appertains.

The general construction of my improved rotary engine is simple and inexpensive, and 75 it is of such a nature as to cause the greatest possible amount of power to be derived from the least expenditure of energy.

The parts of the engine are so constructed and put together as to insure steam-tight 80 joints.

The wear upon various parts of the engine may be very readily compensated for by means of the eccentric sleeves or rings 12 and the guide-arms 14, which latter may be adjusted so as to cause their lower ends to clamp 85 the piston-plate with any desired degree of pressure.

The mechanism for controlling the admission of steam is simple and certain in its operation and may be readily adjusted in a manner described, so as to cause the cut-off to take place at any desired point of the operation of the machine.

Having thus described my invention, I 95 claim—

1. In a rotary engine, a concentric counter-balanced piston-plate arranged to revolve in the cylindrical casing, in combination with the eccentrically-arranged rotary piston-head 100 having the guide-arms for said piston-plate, said guide-arms being connected with the rotary piston-head by means of a roller-joint, as herein set forth.

2. In a rotary engine, the combination, with 105 the casing, of the eccentrically-arranged rotary piston-head, the guide-arms connected with said piston-head by means of a roller-joint, the clamping-screw connecting the outer ends of said guide-arms, and the piston-plate mounted between the latter and secured upon a shaft concentric in the casing, substantially as set forth.

3. In a rotary engine, the combination of 115 the casing, the rotary piston-head having laterally-extending sleeves or tubular arms, the bearings for said arms formed eccentrically in the sides of the casing, and the eccentric bearing rings or bushings mounted adjustably in the ends of the casing, substantially 120 as and for the purpose set forth.

4. In a rotary engine, the combination of 125 the concentric piston-plate, the eccentric rotary piston-head, the guide-arms mounted in the latter by means of the roller-joint, and the counter-weight upon the piston-plate, substantially as set forth.

5. In a rotary engine, the combination of 130 the casing-plate, the eccentric rotary piston-head, the guide-arms mounted in the latter

by means of the roller-joint, the counter-weight upon the piston-plate, the steam inlet and exhaust ports, the cylindrical steam-chest, the oscillating valve mounted in the latter, and the pitman connecting a crank upon the main shaft with a crank mounted adjustably upon the oscillating valve-stem, substantially as and for the purpose set forth.

In testimony that I claim the foregoing as my own I have hereto affixed my signature in presence of two witnesses.

ABNER D. BAKER.
